UNITED STATES PATENT OFFICE.

JOSEPH STUNGO, OF PITTSBURGH, PENNSYLVANIA, ASSIGNOR TO STUNGO-RADIUM
RUBBER COMPANY, A CORPORATION OF DELAWARE.

DESIGN FOR A TIRE.

53,278.

Specification for Design.

Patented May 6, 1919.

Application filed February 2, 1917. Serial No. 146,296. Term of patent 7 years.

To all whom it may concern:

Be it known that I, JOSEPH STUNGO, a subject of the King of Great Britain, residing at Pittsburgh, in the county of Allegheny and State of Pennsylvania, have invented a new, original, and ornamental Design for Tires, of which the following is a specifica-

tion, reference being had to the accompanying drawing, forming a part thereof.

The figure is a perspective view of the tire.

I claim:

The ornamental design for a tire as shown.
JOSEPH STUNGO.
